UNITED STATES PATENT OFFICE.

FÉLIX EMILE VALOIS, OF BRIDGEPORT, CONNECTICUT, ASSIGNEE TO HAMEL SHOE MACHINERY COMPANY, OF BRIDGEPORT, CONNECTICUT, A CORPORATION OF MASSACHUSETTS.

ROUGH ROUNDER OR CHANNELER.

Application filed February 9, 1920. Serial No. 357,311.

To all whom it may concern:

Be it known that I, FÉLIX E. VALOIS, a citizen of the United States, residing at Bridgeport, in the county of Fairfield and State of Connecticut, have invented certain new and useful Improvements in Rough Rounders or Channelers, of which the following is a specification, reference being had therein to the accompanying drawings.

10 In rough rounding and channeling machines as usually constructed, the channeling knife is held in a slot in the upper surface of a knife holder, its forward end being bent substantially parallel to the forward face 15 of the holder where it is provided with a lateral cutting edge, the forward face of the holder furnishing a surface against which the work is held during the channeling operation. As the knife is used and 20 sharpened, it has been found that considerable space may be left between the cutting edge of the knife and the work-engaging surface of the holder which then furnishes no support for the work closely adjacent the 25 cutting edge, impairing the quality of the work of the machine.

To avoid this objection this invention provides an adjustable work-engaging face for the knife holder which may be moved laterally thereof toward the cutting edge of the 30 knife in order to insure support for the work closely adjacent thereto.

Another difficulty experienced with these machines as usually constructed lies in the 35 fact that as the cutting edge of the channel knife is ground away its operative position with relation to the other parts of the machine changes. This matter is of more importance where the above-mentioned adjustable work-engaging face is employed, as the 40 knife may then be ground considerably further back than heretofore without otherwise interfering with the operation of the machine.

45 In order, therefore, to take more complete advantage of the construction above-mentioned, this invention further provides means whereby the edge of the knife may be adjusted relative to other parts of the machine so that repeated grinding may not cause it to be incorrectly related thereto.

More specifically it provides means for accomplishing this adjustment which does not detract from the rigidity of the mounting of 50 the knife within a floating knife block, this

means comprising an eccentric pivot for the knife bar actuating lever by the turning of which the knife block, floating block and knife may be moved together.

For a more complete understanding of 60 this invention reference may be had to the accompanying drawings embodying the same in which—

Fig. 1 represents a side elevation of a portion of the channeling knife bar carrying 65 thereon a floating block comprising the channel knife holder;

Fig. 2 represents a front elevation showing the knife as having been ground away but with the work-engaging plate in its 70 original position;

Fig. 3 is a view similar to Fig. 2 showing the work-engaging plate adjusted toward the knife edge;

Fig. 4 is a top plan of a portion of a 75 rough rounder involving this invention and partly in section, the section being taken on line 4—4 of Fig. 1;

Fig. 5 is a section taken on the line 5—5 of Fig. 1;

Fig. 6 is a perspective view of the channeling knife;

Fig. 7 is a side elevation partly in section of the parts shown in Fig. 4; and

Fig. 8 is a detail partly in section of an 85 adjustable pivot.

In these figures 1 represents a channeling knife bar having an enlargement 2 at its forward end for the reception of a knife holding block 3, this block being mounted by means 90 of mating concentric ribs and grooves, so that it is free to oscillate about a center substantially at the forward upper end thereof. Block 3 is composed of two members 4 and 5, member 5 having a guide pin 6 thereon 95 adapted to engage in a perforation 7 of member 4. A bolt 8 passes through a perforation in the member 4 and engages a screw threaded opening 9 in the member 5, the head 10 of this bolt being carried in a recess 100 11 in the outer face of member 4. Member 4 has along its upper surface a recess 12 and opposite thereto the member 5 has a dove-tail recess 13. The shank 14 of a channeling knife 15 may be positioned 105 within the recesses 12 and 13 and on tightening the bolt 10 may be made fast therein by means of the dove-tail formation of the recess 5 engaging the corresponding portion 110 of the shank 14. As shown, the shank 14 ex-

tends rearwardly from the block 3 and through a slot in the portion 2, the bottom of which at 16 may be engaged by the knife shank to prevent the separation of block 3 from the bar 1 in a downward direction. The forward end of the knife 15 is turned downwardly at 17 into substantially parallel relation to the forward face of the block 3 and is provided at its lateral face with a cutting edge 18.

The member 4 has in its forward face a lateral groove 19 for the reception of a mating tongue 20 carried on the rear face of a work-engaging plate 21. A screw 22, the head of which is seated in a substantially flat recess 23 in the forward face of the plate 21, passing through a slot 24 therein and threaded into the portion 4, serves to retain the plate 21 in position with capability of lateral adjustment across the forward face of the member 4 toward and from the cutting edge 18 of the knife. When the knife is new it is formed substantially as shown in solid line in Fig. 6, but after use and re-sharpening the knife blade becomes narrower as shown by the dotted line. In this condition the cutting edge of the knife is at a substantial distance from the edge of the plate 21 as shown in Fig. 2, which now furnishes no support for the work closely adjacent the knife. On loosening the screw 22, plate 21 may be moved laterally toward the knife edge and fixed in position.

In order to provide for adjusting the cutting edge of the channel knife so that it may be properly presented to the work in relation to other operative mechanisms of the machine regardless of the amount to which the edge of the knife may have been ground back, the mechanism illustrated in Figs. 4, 7 and 8 has been provided, these figures showing the invention applied to a rough rounding machine of the type disclosed in the patent to Valois, 1,118,883, Nov. 24, 1914, to which reference may be had for details of construction, not herein shown.

In these figures, 30 represents the main drive shaft of the machine carrying an eccentric 31. Journaled on this eccentric is the rear end of a link 32 pivoted at 33 to the rear end of a chopping knife bar 34, this bar carrying at its forward end the chopping knife for rough rounding the sole of a shoe after attachment to the welt. Projecting from the lower face of the bar 34 is a pin 35 engaging within an angular slot 36 in a plate 37, this plate forming a cover for a guiding block 38 to which it is attached by screws 39. Block 38 has a channeled, upper face in which channel the channeling knife bar 1 is slidably mounted, a guide pin 40 extending through a slot 41 of the bar 1 and seated in the sides of the block 37 serving to retain the bar 1 in position. Mount-

ed in the frame A of the machine is a stud 42 formed above the frame A as an eccentric 43, surmounted by a concentric knob 44 provided with a transverse opening 45. Within the frame A the stud 42 has a peripheral groove 46 therein, and a set screw 47 seated within the frame A engages within this groove 46 to retain the stud 42 in position and to prevent it from rotating when set screw 47 is tightened thereagainst. Journaled on the eccentric portion 43 is the rear end of a lever 48, the forward end of which is made fast to or is integral with the block 37. If desired an indicating plate 50 may be attached to the stud 42 immediately above the lever 48, this plate carrying a pointer 50^a cooperating with suitable indices marked on the lever 48, by which means the position of the eccentric may be easily determined. Depending from the link 32 is a boss 51. Bearing between this boss and a socket 52 in the rear end of channel knife bar 1 is a coil spring 53 which normally urges the bar 1 to its forward limit of motion as determined by the pin 40 and slot 41. Extending laterally from the bar 1 is a pin 54 which may be engaged by one end of a lever 55 connected to any suitable treadle mechanism (not shown) by which the bar 1 carrying the channeling knife may be retracted against the pressure of the spring 53 by the operator at will, as disclosed in the above-mentioned patent.

The operation of this mechanism is as follows. Rotation of the shaft 30 acting through the eccentric 31 serves to reciprocate the link 32 and the chopping knife bar 34 which imparts the cutting stroke to the edge trimming knife. Movement of the pin 35 within the slot 36 causes a lateral movement of the channel knife bar 1 due to the angular position of the slot 36 with relation to the plate 37, this motion giving the operative movements to the channel knife block and hence to the channel knife 15. The spring 53 holds the channel knife block outwardly against the work, the force of the spring being increased on the outward stroke of the bar 34 and the working stroke of the channel knife, by the motion of the lug 51 toward the rear end of the bar 1, this action being substantially as shown and described in the patent to Valois, above noted. As the channel knife 15 is ground away the cutting edge thereof travels relative thereto toward the left as shown in Figs. 2 and 4. In order to adjust it into proper relative position to the chopping knife it is only necessary to release the set screw 47 slightly, insert a suitable tool in the opening 45 in knob 44 and turn the stud 42, the eccentricity of the portion 43 moving the fulcrum of the lever 48, turning the lever 48 about the pin 35 as a center and swinging the forward end of the bar 1 and with it the cutting edge 130

of the knife. By suitably positioning the eccentric 43, it is thus seen that the bar 1 and block 3 may be adjusted to suit the position of the cutting edge of the channel 5 knife to adjust the initial and final positions of its path of motion in proper relation to the other parts of the machine. By this means it may be seen that the knife blade can be sharpened till its width is materially 10 decreased without detracting from the quality of its work.

While this invention has been shown as applied to a channeling knife holder, it will be evident to those skilled in the art that it 15 may also find application in other situations where it is desired to support work closely adjacent the working portion of a tool, the position of which may vary from time to time.

Having thus described one embodiment of 20 this invention what is claimed is,—

1. In a machine of the class described, in combination, a tool-holder, a knife carried thereby and having a blade offset from and substantially parallel with one face of said holder, a work-supporting plate having a work-engaging face substantially parallel with said blade, and means for relatively adjusting the adjacent edges of said blade 25 and work-supporting plate edgewise toward and from each other.

2. In a shoe machine, a knife holder, a knife carried by said holder and having a cutting edge spaced from and substantially 30 parallel to one face of said holder, a work-engaging plate carried on said face and adjustable toward and from said knife, and means for mounting said holder in such manner that it may conform freely to the angular 35 position of work presented against said plate.

3. In combination, a channel knife block, a channel knife carried thereby and having a blade provided with a laterally facing cutting edge projecting over that face of said 40 block positioned adjacent the work, and a work-engaging plate slidably mounted on the said face of said block and adjustable toward and from the cutting edge of said 45 knife.

4. In a machine of the class described, a main-shaft, a chopping-knife bar operated from the latter and provided with a pin, a lever provided with a guide-block having an angular slot, a stud circularly adjustable upon the machine frame and provided with an eccentric portion affording a fulcrum for said lever, said pin and guide-slot cooperating to swing said lever through a path determined by the adjustment of said stud.

5. In a machine of the class described, a main-shaft, a chopping-knife bar operated from the latter and provided at its free end with an enlargement, a knife-holding block 60 provided with a knife and adjustably se-

cured in said enlargement, an eccentric, and a lever journaled on the latter and operatively connected with said chopping-knife bar for giving to said knife operative movements.

6. In a machine of the class described, a main-shaft, an actuating eccentric thereon, a link provided with a laterally extending boss and operatively connected with said eccentric, a reciprocating chopping-knife bar 70 operatively connected with said link, a lever provided with a spring-receiving socket, a circularly adjustable eccentric upon which said lever is fulcrumed, a channeling knife mounted upon the free end of said lever, and a spring seated within said socket and 75 engaging the lateral boss of said link to urge said channeling knife to its limit of movement upon said lever.

7. In a rough rounding machine, a lever, 80 a channel knife bar carried by said lever, a channel knife carried by said bar, a shaft, a chopping knife bar, means actuated from said shaft for reciprocating said chopping knife bar, means operatively connecting said 85 chopping knife bar and said channel knife bar whereby reciprocation of said chopping knife bar swings said channel knife bar about the fulcrum of said lever, and means for adjustably fixing the position of said fulcrum to adjust the limits of the path of motion of said channel knife.

8. In a rough rounding machine, a lever, 90 a channel knife bar carried by said lever, a channel knife carried by said bar, a shaft, a chopping knife bar, means actuated from said shaft for reciprocating said chopping knife bar, a pin-and-slot connection between 95 said chopping knife bar and said channel knife bar whereby reciprocation of said chopping knife bar swings said channel knife bar about the fulcrum of said lever, and means for rocking said lever about the pin of said pin-and-slot connection to move 100 said knife.

9. In a rough rounding machine, a lever, 105 an eccentric on which said lever is fulcrumed, a channel knife bar carried by said lever, a channel knife carried by said bar, a shaft, a chopping knife bar, means actuated from 110 said shaft for reciprocating said chopping knife bar, a pin-and-slot connection between said chopping knife bar and said channel knife bar whereby reciprocation of said chopping knife bar swings said channel knife bar about the fulcrum of said lever to impart operative movement to said channel knife, and means for turning said eccentric to move said fulcrum and swing said lever about the pin of said pin-and-slot connection to adjustably position the path of operative movement of said channel knife.

In testimony whereof, I have signed my name to this specification.

FÉLIX EMILE VALOIS.
